UNITED STATES PATENT OFFICE

ROBERT A. CURRIE, OF SYRACUSE, NEW YORK, ASSIGNOR TO R. E. DIETZ COMPANY, OF NEW YORK, N. Y.

LANTERN

Application filed November 12, 1929. Serial No. 406,629.

This invention relates to lanterns, and more particularly to means by which a lantern may be converted from an oil burning lantern to an electric lantern, and vice versa.

5 An object of the invention is to provide improved and simple means for converting the ordinary oil burning lantern of the removable fount type into an electric lantern; with which the electric lantern may be converted 10 back into an oil burning lantern whenever desired; with which the cost of conversion of an oil burning lantern into an electric lantern will be relatively slight; with which the conversion may be accomplished in a simple and easy manner; with which an emergency oil burning light may always be available in the event of failure of the electric light; and which will be relatively simple and inexpensive.

20 Various other objects and advantages will be apparent from the following description of an embodiment of the invention, and the novel features will be particularly pointed out hereinafter in connection with the appended claims.

In the accompanying drawings:

Fig. 1 is a front elevation of an ordinary railroad signal lantern of the type having a removable oil fount, when converted into an 30 oil burning lantern;

Fig. 2 is a transverse, sectional elevation of the lower portion of the same, when converted into an electric lantern;

Fig. 3 is a front elevation of the electric conversion unit removed from the lantern;

Fig. 4 is a sectional elevation through the upper portion of the same to illustrate certain details of construction, the switch member being in "on" position;

Fig. 5 is a similar view, but with the switch member in "off" position;

Fig. 6 is a bottom plan of the top or removable cover of the unit;

Fig. 7 is a sectional plan of the unit, with one of the battery cells removed; and

Fig. 8 is a perspective, partly in section, of the conversion unit with the top removed.

In the illustrated embodiment of the invention, the lantern is of the railroad signal type, and includes the usual frame or guard

1, with the cup-like base shell 2 opening upwardly so as to receive the usual removable oil fount with burner *a* (Fig. 1) and with operating stem *b*. The oil founts of railroad signal lanterns are of standard size. 55 The shell 2 is provided along its upper open edge with a globe seat 3 (Fig. 2) surrounded by an upstanding flange 4. A globe 5 of transparent material, such as glass, is removably mounted on the seat 3 within the flange 60 4; and is confined to the seat by the usual globe holder 6 (Fig. 1) carried by the dome 7 and spring pressed downwardly upon the top of the globe by means of the usual spring, not shown, within the dome. The dome is of 65 the hinged type to permit removal of the globe and of the oil fount.

The conversion unit, shown separately in Fig. 3, includes a cylindrical shell 8 having a removable cover 9. A partition 10 is disposed in the shell and forms approximately cylindrical cavities A and B of a size to receive pocket flash light battery cells of a standard size, with the cells extending vertically. A pair of insulating discs 11 and 12, 75 Fig. 2 are disposed in the bottom of the shell, and a contact strip 13 of spring metal is disposed between the discs and against the central portion of the underface of the upper disc with its ends threaded upwardly 80 through the upper disc and then extending slightly above the upper face of the upper disc 12, into the centers of the bottoms of cavities A and B, as shown clearly in Figs. 2 and 7.

A pair of flash light batteries 14 and 15 are disposed in the shell 8, one in the cavity A and the other in the cavity B. One of the cells, such as 15, is disposed in an upright position in its pocket or cavity B and the other cell 14 is disposed in its pocket A in an inverted position. The central electrode of the inverted cell rests upon the projecting flexible end of the contact strip 13, so as to have electrical connection therewith, and the exposed metal bottom of the upright cell 15 rests upon the opposite flexible end of the contact strip 13, with the result that the two cells are thus connected electrically in series with one another. 100

The cover 9 is provided with an outwardly struck boss 16, having a threaded aperture 17 that mounts the threaded end of an electric light bulb 18 of the flash light or low voltage type. The base of the bulb 18 screws in to the metal boss 16 and grounds one terminal of the bulb to the shell cover. A contact spring 19 is secured to the under face of the cover 9 in any suitable manner, such as by a rivet 20, the securing means or rivet grounding the contact spring to the cover of the casing. The free end of the contact spring 19 bears resiliently and resiliently upon the central electrode of the upright battery cell 15 when the cover is placed on the casing.

The inner face of the cover is provided with an insulating layer or lining 21 (Figs. 2 and 6), and a disk 22 of insulating material is secured against the underface of the cover, such as by the rivet 20 (Figs. 4 and 5). A conducting strip 23 of spring metal is threaded through the disc 22 at a couple of spaced points, one end of the strip 23 extending across the inner end of the passage 17 in the boss 16 so as to engage resiliently with, and establish an electrical circuit to, the central end contact of the light bulb 18.

The other end of the strip 23 bears flexibly and resiliently upon the metal bottom end of the inverted battery cell 14. The portion of the strip 23 between the apertures in the disc 22 through which it passes will lie flat against the inner face of the lining layer 21, so as to be insulated from the top cover 9, and the strip 23 may be held against removal or displacement by a rivet 24a, Fig. 2, which passes through the disc 22 and the strip 23.

An electric circuit for the lamp or bulb 18 is thus established as follows: From the central electrode of the upright battery 15 through spring contact 19 to the cover 9 of the shell 8, thence through boss 16 to the threaded contact ferrule on the base of the light bulb, through the bulb to the central end contact of the bulb, thence through strip 23 to the outer shell or electrode of the inverted battery cell 14, through the battery cell 14 to the central electrode thereof, thence through conducting strip 13 to the outer shell or electrode of the upright battery cell 15, and thence through the cell 15 to the central electrode where the circuit as described started. By flexing the contact 19, out of engagement with the central electrode of the upright battery cell 15, the circuit to the light bulb will be broken, and when the spring 19 is released, it will spring back into engagement with the central electrode of the battery 15 and again complete the circuit.

In order to operate the contact 19 to make or break the circuit from the exterior of the shell, a suitable device is provided for mechanically camming the contact or spring 19

out of engagement with the battery electrode. For this purpose, a sheet metal arm 24 may be secured, such as by rivet 25 to the cover 9 so as to depend from the underface thereof and adjacent the periphery thereof. The depending end of the arm 24 is provided with a rolled bearing 26 in which a stem 27 is slidably mounted. The stem 27 extends outwardly from the cover 9 in the position corresponding to the usual position of the wick operating stem of an oil fount that is adapted to fit the same base 2, and its outer end is provided with an operating button 28.

The depending arm 24 is provided at its lower end with a branch 29 which extends toward the center of the shell 8, so that the depending arm 24 is somewhat L-shaped. The inner end of the stem 27 is bent angularly at 30 (Figs. 4 and 5), so as to lie along one face of the arm 24, and is then bent laterally across the upper edge of the branch 29 to form a contact operating arm 31.

The operating arm 31, at its free end, carries a cam or plate 32 of fiber, rubber or other insulating material in a position to engage with the spring or contact 19 and cam it upwardly away from the battery cell 15 when the stem is pushed inwardly. The free end of the branch 29 cooperates with the stem to limit inward movement of the stem, and for this purpose the extreme free end of the branch 29 may be flanged laterally as at 33 to lie in the path of movement of the angular portion 30 of the stem when the stem is pushed inwardly.

The flanged end 33 of the branch 29 is so located that it will stop the inward movement of the stem 27 after the cam 32 has forced the spring contact 19 upwardly away from the battery cell sufficiently to cause the free end or contact portion of the spring 19 to ride upon the upper face of the cam 32, in which position the spring or contact 19 will exert its resilient force on the cam in a direction laterally of its path of movement, so as not to urge the cam and stem outwardly. Thus when the stem is pushed inwardly to open the circuit to the lamp, the stem will be frictionally retained in "off" position by the pressure of the spring 19 upon the upper face of the cam.

Extra lamp bulbs may be carried in the interior of the shell 8 at one side of the double partition wall 10, and the batteries do not usually give out suddenly without warning, but indicate their weakness through the dimming of the light emitted by the bulb 18. In the event of any unforeseen or sudden failure of the electric unit of the lantern, however, provision for an emergency oil light may be made. For example, a small oil fount 34 may be disposed also in the shell 8 at the side of the double partition opposite from the space that may be used for extra

bulbs, the casing of the fount being formed to fit the undulatory shape of the partition 10 and the curved shape of the shell 8 so as to have maximum capacity for oil.

5 The fount 34 is provided with a suitable burner 35 having a wick 36 extending therefrom and disposed immediately below the cover 9, preferably as near as possible to the center of the casing 8. Thus if the electrical 10 illumination fails, one may remove the cover 9 of the conversion unit, and light the wick 36 which will burn and provide an emergency light within the globe, the same as would be provided were an oil fount used to replace 15 the conversion electric unit.

The illustrated lantern, as shown in Fig. 1, is of the type commonly used for railroad signalling, by railroad employees, and has the usual draft openings for supplying air to the 20 interior of the globe for combustion purposes and for removing the products of combustion. Such lanterns heretofore have been provided with removable oil founts, each carrying a suitable burner and a wick *c* (Fig. 25 1), the wick operating stem *b* thereof extending outwardly through a notch 37 (Fig. 1) provided in the flange 4 and the globe seat 3, the globe confining the wick operating stem in the bottom of the notch and thereby preventing displacement of the fount in the 30 base 2.

To convert such an oil burning lantern into an electric lantern, the dome 7 is removed or lifted to release the globe 5, the globe being 35 then removed, after which the oil fount is removed. The conversion unit, shown separately in Fig. 3, which is of a size and shape to fit the cavity in which the oil fount was carried in the lantern base 2, is then placed in 40 the base 2 in the position formerly occupied by the oil fount. The stem 27 is received in the notch 37, and the globe 5 is then replaced and the dome 7 closed, as shown in Fig. 1. The globe confines the stem 27 in the bottom 45 of the notch 37, and thus holds the conversion unit against displacement in the base 2.

To light the converted lantern, it is merely necessary to pull outwardly on the button 28, whereupon the cam 32 on the inner end of 50 the stem releases the contact spring 19, and the latter thereupon springs into engagement with the central electrode of cell 15 to complete the electric circuit to the bulb, as shown in Fig. 4. To extinguish the light, it is merely necessary to push inwardly on the button 28, which cams the contact 19 into open circuit position as shown in Fig. 5.

If the electric circuit fails unexpectedly, the cover 9 of the unit may be removed, and the wick 36 lighted to provide an emergency light until a new unit 8 can be obtained and substituted in the base 2, or new batteries or bulbs obtained and substituted for the defective elements.

65 It will be obvious that various changes in

the details, which have been herein described and illustrated in order to explain the nature of the invention, may be made by those skilled in the art within the principle and scope of the invention as expressed in the appended claims.

Claims:—

1. A lantern comprising a frame of the oil burning type having an upwardly opening, cup-shaped fount receiving base with a 75 globe seat adjacent its upper open edge, said seat having a notch to receive the wick operating stem of a liquid fuel burner and oil fount, a shell removably fitted in said cavity and having a removable cover and a stem extending outwardly through said notched seat, an electric light bulb mounted on the cover of said shell, means in said shell and controlled by said stem for lighting or extinguishing said bulb, an emergency oil fount 80 and burner also carried wholly within and concealed by the cover of said shell, and a globe releasably mounted on said seat to confine said shell and stem in said base.

2. A lantern comprising a frame of the oil burning type having an upwardly opening, oil fount receiving cup-shaped base with a globe seat along its upper end edge, said seat having a notch to receive the wick operating stem of a liquid fuel burner and oil fount, a shell removably fitted in said cavity 95 and having a stem extending outwardly through said notched seat, an electric light bulb mounted on said shell, means in said shell and controlled by said stem for lighting or extinguishing said bulb, a globe releasably mounted on said seat to confine said shell and stem in said base, said shell having a removable cover, and an emergency oil fount disposed also in said shell and having a wick immediately beneath said cover, whereby if said electric light bulb fails to function, said cover may be removed and said wick lighted to provide an emergency light.

3. In a lantern member, an electric unit comprising a casing having a removable cover, battery means removably mounted in said casing, a bulb mounted on said cover, circuit means carried by said cover and including a spring contact engageable directly with said battery means to complete an electric circuit between said bulb and said battery means when the cover is applied to its casing, a stem extending outwardly of said casing, and an insulated cam carried by the inner end of said stem and operable with the stem to force one of said contact elements out of engagement with said battery means to interrupt the circuit to said bulb and extinguish the light.

4. In a lantern member, an electric unit comprising a casing having a removable cover, battery means removably mounted in said casing, a bulb mounted on said cover, 130

circuit means carried by said cover and including a spring contact engageable with said battery means to complete an electric circuit between said bulb and said battery
5 means when the cover is applied to its casing, a sheet metal arm secured to the under face of said cover and depending therefrom, the lower end of said arm being rolled to provide a bearing, a stem mounted in said bearing and extending outwardly of the cover, a cam mounted on said stem in a position to effect a disconnection of one of said contact elements from said battery means upon operation of said stem in one direction.
10 5. In a lantern member, an electric unit comprising a casing having a removable cover, battery means removably mounted in said casing, a bulb mounted on said cover, circuit means carried by said cover and including a spring contact engageable with said battery means to complete an electric circuit between said bulb and said battery
15 means when the cover is applied to its casing, a sheet metal arm secured to the under face of said cover and depending therefrom, the lower end of said arm being rolled to provide a bearing, a stem mounted in said bearing and extending outwardly of the cover, a cam mounted on said stem in a position to effect a disconnection of one of said contact elements from said battery means upon operation of said stem in one direction, said stem and arm having cooperating portions for limiting the movement of said stem.
